VALDEMAR SCHMIDT, OF LOS ANGELES, CALIFORNIA, ASSIGNOR OF ONE-HALF TO
JOHN S. HENDERSON, OF LOS ANGELES, CALIFORNIA.

AUTOMATIC SILENT RAILROAD-CROSSING.

1,288,222.

Specification of Letters Patent.

Patented Dec. 17, 1918.

Application filed December 18, 1917. Serial No. 207,729.

To all whom it may concern:

Be it known that I, VALDEMAR SCHMIDT, a citizen of the United States, residing at Los Angeles, in the county of Los Angeles 5 and State of California, have invented new and useful Improvements in Automatic Silent Railroad-Crossings, of which the following is a specification.

My object is to make an improved silent 10 railway crossing which may be automatically operated by the approaching cars, and my invention consists in the novel features herein shown, described and claimed.

Figure 1 is a plan showing two railroad tracks crossing two other railroad tracks at right angles, the tracks being provided at their intersections with automatic silent crossings in accordance with the principles of my invention.

Fig. 2 is a fragmentary detail perspective showing one railroad track crossing another at right angles, the tracks being provided with my automatic silent crossing.

Fig. 3 is a fragmentary plan at a point 25 where one railway crosses another at right angles, parts being broken away and shown in section, the view being taken looking downwardly in Fig. 4.

Fig. 4 is a vertical cross-section on the line 4—4 of Fig. 3.

Fig. 5 is a plan view showing two main line tracks each having a turn-out or branch, the branch of one track crossing the other track.

Fig. 6 is an enlarged fragmentary plan at the point —a— in Fig. 5 where the branch rail leaves the main line rail.

Fig. 7 is a vertical cross-section on the line 7—7 of Fig. 6.

Fig. 8 is an enlarged fragmentary plan of the operating mechanism for closing the switch and at the point —b— in Fig. 5.

Fig. 9 is a fragmentary vertical sectional detail on the line 9—9 of Fig. 8.

Fig. 10 is an enlarged fragmentary plan at the point —c— in Fig. 5 where the branch rail shown in Fig. 6 crosses the main line rail.

Fig. 11 is an enlarged fragmentary plan at the point —d— in Fig. 5 where the branch rail of the right-hand track crosses the left hand track.

Fig. 12 is a perspective of one of the movable track sections shown in Figs. 1, 2, 3 and 4.

Fig. 13 is a perspective of the movable track section shown in Fig. 10.

Fig. 14 is a perspective of the movable track section shown in Fig. 6.

Fig. 15 is a perspective of the movable 60 track section shown in Fig. 11.

My automatic silent railway crossing is especially adapted for street railways and the like where the cars all run one way on one track and the other way on another 65 track, and the system I will show and describe is intended to operate in one direction only on a given track.

In Fig. 1, it will be assumed that the cars will run in the direction indicated by the 70 arrows 1, 2, 3 and 4. Movable track sections 5 are inserted at each point where one rail 6 crosses another rail 7.

A movable track section 5 is shown in detail in Fig. 12 and consists of a circular 75 flat base plate 8, and a rail connecting plate 9 formed integral with the base plate 8 diametrically across its upper face and having track edges 10 and 11. A spindle 12 extends downwardly from the center of the 80 base 8 and spur gears 13 and 14 are fixed upon the spindle.

In Fig. 2, I have shown the line 15 crossing the line 16 in Fig. 1 and in Figs. 3 and 4 I have shown the details of the intersection 85 17 in Figs. 1 and 2. The crossing 18 shown in Fig. 2 is made up of four intersections like that shown at 17 the surface of the track consisting of plates 19, 20, 21 and 22.

A housing 23 is mounted below 90 each intersection 19, 20, 21 and 22, and a circular recess 24 is formed in the intersection to receive the base plate 8, and the spindle 12 extends downwardly through the surface plate and through the box 23 into a bearing in the lower side of the box. The base 8 and the recess 24 are located so that the edge 10 will line up with the track edge 95 25 of the track 16 and the track edge 11 will track up with the track edge 26 of the line 15.

The track edges 10 and 11 are parallel with each other in a right angled crossing and it takes a quarter turn of the base 8 to change the crossing from one track to the other, that is, to swing the track edge 10 out of alignment with the track edge 25 and swing the track edge 11 into alignment with the track edge 26, and vice versa. The track edges 10 and 11 are a considerable distance apart and parallel with 100

105 the base 8 to change the crossing from one track to the other, that is, to swing the track edge 10 out of alignment with the track edge 25 and swing the track edge 11 into alignment with the track edge 26, and vice versa. The track edges 10 and 11 are a considerable distance apart and parallel with 110

each other, and in order to bring these edges in line with the rails, the spindles 12 are located out of line with the tracks. This brings the centers of the base plates 8 out 5 side of the fixed tracks and at angles of 45°, relative to the inner edge of the fixed tracks, so that the larger portions of the base plates are outside of the tracks. Gear racks 27 and 28 are mounted in the housing 23 at 10 right angles to each other and in mesh with the gears 13 and 14, respectively. A draw bar 29 connects the racks 27 in the housings under the intersections 19 and 22 and a similar draw bar 30 connects the racks 28 in the 15 housings under the intersections 19 and 20. In a like manner the racks in the housing 20 20 31 extends from the draw bar 29 down the track and is connected to the crossing actuator 32 so that as a car approaches the crossing going in the direction indicated by the arrow 1 in Figs. 1 and 2 the flange of 25 the forward car wheel will strike the actuator 32 and throw the movable track members 33, 34, 35 and 36 into line so that the track edges 10 will line up with the track edges 25 and make a continuous surface to 30 carry the wheels over the grooves 37 in the other track.

The movable track members 33, 34, 35 and 36 are each constructed like the track section 5 shown in Fig. 12. A spring 38 is 35 incorporated into the line with the operating draw bar 31. The actuator 32 has a head 39 mounted upon a pivot 41 in an opening 40 in the rail plate. An arm 42 extends downwardly from the head 39 below 40 the pivot 41 and has a series of bearing recesses 43 in one side. A hook 44 is formed upon the end of the spring 38 to engage in the recesses 43, the tension of the spring or the adjustment of the parts being regulated 45 by moving the hook 44 from one recess to another. A plate 45 is bolted to the arm 42 to hold the hook 44 in the desired one of the recesses 43. A set collar 46 is mounted upon the operating draw bar 31 upon the 50 opposite side of a bearing 47 from the spring 38 so that by adjusting the position of the set collar 46 the line up of the movable track sections may be adjusted to a nicety, the spring 38 yielding after the set collar 46 55 strikes the bearing 47.

An actuator 48 is mounted in the line 15 and connected to the intersections 33, 34, 35 and 36 so that when a car approaches the crossing in the direction indicated by the 60 arrow 3 the front wheel will actuate the actuator 48 and turn the movable track members and bring the track edges 11 into line with the track edges 26 so that the car wheels will pass noiselessly over the grooves 65 49 in the track 16.

The intersections 19, 20, 21 and 22 are substantially alike. Each is a right-angled cross having arms of equal length and having the grooves 37 and 49 in their upper faces, so that when the four intersections 70 are placed together in the form of a square the track crossing is complete.

The housings 23 have extensions 50 extending beyond the intersection plates and are provided with covers 51 through which 75 the mechanisms in the housings are more or less accessible.

The draw bars 29 and 30 are mounted in suitable bearings 52 located in the housings 23 and extend through tubes 53 extending 80 through the ties 54 or between the ties, as the case may be.

The racks 27 and 28 are preferably located upon the outer sides of the gears all 85 the way around.

The operating bars 31 may be extensions of the bars 29 or they may be spliced onto the racks or bars in any suitable way.

In Fig. 5 the cars are supposed to run upon the main line track 55 in the direction 90 indicated by the arrow 56 and upon the branch track 57 in the direction indicated by the arrow 58, and the returning cars are supposed to run upon the main line track 59 in the direction indicated by the arrow 95 60 and upon the branch track 61 in the direction indicated by the arrow 62. The main line 55 is normally open and the switch to the branch track 57 is normally closed. The movable track section 64 shown in Fig. 100 14 is similar to the movable track section 5 shown in Fig. 12 except in the shape of the rail connecting plate 64, said plate being wedge-shaped in plan and having track edges 65 and 66. Referring to Figs. 5, 6 105 and 7, the track edge 65 is in line with the groove 67 in the main line rail. A housing 68 is mounted below the intersection track plate 69 and has an extension provided with a cover 70. The rail connecting plate 64 is 110 formed integral with the base 71 and this base is recessed downwardly into the track plate 69 and a spindle 72 extends downwardly through the track plate and has gears 73 and 74. A rack 75 meshes with 115 one of the gears and the draw rod 76 is connected to this rack. A housing 77 is mounted between the main line rails in front of the intersection and a pivot shaft 78 is mounted in this housing crosswise of the 120 track. An arm 79 is fixed upon the pivot shaft 78 and extends downwardly and is connected to a spring 80 and said spring 80 is connected to the end of the draw rod 76.

An actuator 81 is fixed upon the shaft 78 125 in a slot 82 in the guide frame 83, said guide 83 being mounted between the main line rails. The car will carry a trip which is extended downwardly by the motorman as the car approaches the switch and the trip 130

will engage the actuator 81 and move the upper end forwardly in the slot 83 thereby rocking the shaft 78 and throwing the arm 79 backwardly, thereby pulling on the draw bar 76 and rack 75 to move the rail connecting plate 64 so as to close the slot 67 and bring the track edge 66 into line and run the car onto the branch line 57.

Referring to Figs. 8 and 9, the housing 84 is mounted beside the switch rail beyond the second main line track at the point —b— in Fig. 5 and a draw rod 85 extends from this housing to a rack 86 in mesh with one of the gears 73 or 74. A spring 87 is connected to the end of the draw rod 85 and connected to an actuator arm 88 carrying the actuator head 89 mounted upon a pivot 90 in an opening 91 of the rail plate. A set collar 92 is adjustably fixed upon the draw rod 85 near a bearing 93, and a perforated ear 94 extends from the set collar 92. After a train of cars longer than the distance between the actuators 81 and 89 has advanced far enough to open the switch to the branch line, an operator must go to the point —b— and insert a pin 95 through the ear 94 into the housing so that when the car wheels run over the actuators 81 and 89 they will not slam the switch members back and forth, the spring 87 yielding during this operation, and then when the cars have passed, all but the last wheel, beyond this point, the pin 95 must be withdrawn. The last wheel will move the actuator 89 to close the switch and open the main line. When there is but one car passing the track and the distance between the actuators 81 and 89 is greater than the car length, the device operates automatically and the switch is set for the passage of the next car.

Referring to Fig. 10, the track connecting plate 96 at the point —c— in Fig. 5 is similar to the track connecting plate 64, except that the plate is more pointed and shorter, as shown in detail in Fig. 13, and has track edges 97 and 98. The intersecting track plate 99 has crossing grooves 100 and 101. A housing 102 is mounted below the track plate and is provided with a cover 103. The mechanism in the housing 102 is similar to the automatic mechanism shown in Fig. 2, there being an actuator 104 for the branch track and an actuator 105 for the main line track. When the car is to go on the main line, the actuator 105 will be operated to throw the track edge 97 into line with the groove 101 and the parts will stay in this

position until a car is to go on the branch line. When a car has passed the switch to go on the branch line, the actuator 104 will be operated to throw the track edge 98 into line with the groove 100. The parts will stay in this position until another car passes on the main line.

Referring to Fig. 11, the track connecting plate 106 at the point —d— in Fig. 5 is shown in Fig. 15 and this plate is similar to the plates 64 and 96 except that the track edge 108 is practically straight and serves for both tracks, the second position being indicated by the dotted line 107. This track connecting plate is automatically operated both ways the same as the plate 96.

In a similar manner, automatic crossings are placed at each rail intersection, the details being varied to suit the angularity of the intersection and other conditions.

Various changes may be made in the details of construction without departing from the spirit of my invention as set up in the following claims.

I claim:

1. In an automatic silent railroad crossing, an intersection plate having track grooves and track faces and having a circular recess intersecting the grooves and faces, a rail connecting plate rotatably mounted in the recess and having track edges adapted to line up with the track edges of the intersection plate, and means for operating the rail connecting plate from an approaching car; said means including a spring, an arm pivotally mounted, the spring being adjustably connected to the lower end of the arm, and an actuator head upon the upper end of the arm in position to be engaged by the car wheels, so that by properly adjusting the actuator, the track faces will be lined up by the passage of various car wheels.

2. In an automatic silent railroad crossing, a rail connecting plate adapted to be rotatably mounted, and means for operating the rail connecting plate from an approaching car; said means comprising an arm pivotally mounted, a spring adjustably connected to the lower end of the arm, an actuator head upon the upper end of the arm in position to be engaged by the passing car wheels, a rod connected to the spring, a gear rack upon the rod, a spindle connected to the rail connecting plate, and a gear upon the spindle in mesh with the rack.

In testimony whereof I have signed my name to this specification.

VALDEMAR SCHMIDT.
